UNITED STATES PATENT OFFICE.

SVEN J. STRID, OF CHICAGO HEIGHTS, ILLINOIS, ASSIGNOR TO WILLIAM H. MINER, OF CHAZY, NEW YORK.

DOOR-OPERATING MECHANISM.

1,338,755.

Specification of Letters Patent.

Patented May 4, 1920.

Application filed November 1, 1917. Serial No. 199,758.

To all whom it may concern:

Be it known that I, SVEN J. STRID, a citizen of the United States, residing at Chicago Heights, in the county of Cook and State of Illinois, have invented a certain new and useful Improvement in Door-Operating Mechanism, of which the following is a full, clear, concise, and exact description, reference being had to the accompanying drawings, forming a part of this specification.

This invention relates to improvements in door operating mechanism, and more particularly, to door operating mechanism for refrigerator cars.

One object of the invention is to provide a simple, easily operable and efficient mechanism for positively forcing pivoted doors, such as refrigerator car doors, to fully closed position and also to positively open the doors.

More specific objects of the invention are to provide a door operating mechanism of the general type above indicated wherein is employed a rotatable shaft having gear teeth thereon which coöperate with fixed rack keepers; and to provide a rack and gear operating mechanism having a variable leverage ratio so designed that the maximum leverage is obtained in closing the door during the final movement and also during the initial movement in the opening operation.

In the drawing forming a part of this specification, Figure 1 is a side elevation of a portion of a side wall of a refrigerator car showing my improvements in connection therewith, the doors being illustrated in closed position. Fig. 2 is a horizontal enlarged sectional view, taken substantially on the line 2—2 of Fig. 1. Fig. 3 is an enlarged vertical sectional view, taken substantially on the line 3—3 of Fig. 1, parts being broken away to avoid crowding of the drawing. Fig. 4 is a view similar to Fig. 2, but illustrating the position of the parts when the door is partly open. Fig. 5 is a view similar to Fig. 2, illustrating another embodiment of the invention.

Referring first to the structure illustrated in Figs. 1 to 4, 10 denotes the threshold of the door frame of a refrigerator car, 11 the lintel, and 12—12 the side posts. As is usual

in refrigerator car doors, two pivoted door members are employed, the same being 55 designated as 13 and 14. The former is adapted to be closed first and is provided with an inclined or beveled edge 15 with which coöperates the corresponding beveled or inclined edge 16 of the door member 14. 60 As is also usual, insulating packing is employed to seal the joint between the beveled edges 15 and 16, said insulation being indicated diagrammatically at 17 in Fig. 2, and as will be understood, the insulating packing 17 necessitates forcing the door member 14 to closed position with considerable pressure. Each of the door members 13 and 14 is preferably pivotally mounted on three sets of hinges for each, as indicated at 70 18—18.

For closing, locking and opening the door, the following arrangement is employed: Secured to the lintel 11 is a combined rack and keeper 19 and to the threshold 10 is secured a corresponding rack and keeper 20 differing somewhat in details as hereinafter described from the rack and keeper 19. Each rack and keeper 19 and 20 is provided with a relatively short rack 75 21 curved on an arc concentric with the pivotal axis of the door member 14, and, for strength, each of the racks 21 is braced by flanges 22 and 23. Mounted on the door member 14 are two bearings 24—24 adjacent the upper and lower edges of the door member, as clearly indicated in Fig. 1. Rotatably mounted in said bearings 24 is the operating shaft, designated generally by the reference A. Said shaft A, as shown, is 90 preferably made in three pieces, a central rectangular bar 25 which may be of commercial form, and upper and lower end castings 26—26. Each end casting 26 is forked at its inner end, as indicated at 95 26'—26' so as to fit over the adjacent end of the bar 25 and to which it is rigidly secured as by rivets 27. Each end casting 26 is further provided with a journal section 28 fitting in the corresponding bearing 24 100 so that the shaft A is easily rotatable. It will also be noted that shoulders 29 are formed on the end castings 26 so as to limit the vertical movement of the shaft A with respect to the bearings 24.

On the extreme ends of the castings 26

are formed partial gears 30—30, the same being adapted to coöperate with the racks 21. In addition, each end casting 26 is provided with a somewhat elongated finger or 5 projection 31 which, when closing the door member 14, is adapted to engage the end 32 of the corresponding rack keeper 19 or 20, as clearly shown in Fig. 4. By this arrangement, proper engagement of the gears and 10 racks is insured since the operator, when bringing the door member 14 to closed position, so positions the shaft A that said projections 31 will engage the ends 32 of the keepers before he begins to rotate the 15 shaft and thus effect the final closing movement of the door member 14. After the parts have been engaged, as shown in Fig. 4, the operator will, of course, turn the shaft A by means of the pivoted lever handle 33 20 so that, as the gears 30 are rotated and mesh with the racks 21, the door member 14 is forced to its fully closed position. When this condition has been reached, the lever handle 33 is locked in position by means of 25 a keeper 34 of well known form and the lead seal applied in the usual manner. In opening the door, the shaft A is rotated in a reverse direction and as the projections 31 finally engage the ends 32 of the keepers, 30 continued rotation of the shaft will, through the instrumentality of said projections 31, force the door member 14 positively free of the other door member 13 so that the door member can then be readily swung to fully 35 open position.

The lower rack keeper 20 is forked at its left hand end, as viewed in Figs. 1 and 2, and has pivotally mounted within the fork, a dog 35 which, when in the position shown 40 in Fig. 1, is adapted to prevent any opening movement of the door member 13 during the closing or opening movements of the door member 14.

In the structure illustrated in Fig. 5, the 45 partial gears 130 are disposed eccentrically with respect to the axis of rotation of the shaft A and in such a manner that the distance from the axis of rotation of the shaft A to the teeth of the gear 130 gradually decreases as the shaft is rotated in closing the door. This is done so that a variable leverage ratio is obtained with the maximum leverage at the final closing movement of the door when the resistance against closing is 50 greatest. Similarly, in opening the door, the maximum leverage is obtained at the beginning of the opening movement which is of great practical advantage in connection with refrigerator cars inasmuch as it is 55 quite common for the doors to be frozen together during the winter season. Also, in the construction illustrated in Fig. 5, the rack 121 is curved not only to compensate for the bodily movements of the shaft A as 60 the door member by which it is carried

swings, but also to compensate for the eccentric mounting of the gears 130 with respect to the axis of rotation of the shaft A.

Although I have herein shown and described what I now consider the preferred 70 manner of carrying out my invention, the same is merely illustrative and I contemplate all changes and modifications that come within the scope of the claims appended hereto.

75 I claim:

1. In a car door operating mechanism, the combination of a pair of hinged doors, adapted to be forced into tight engagement along their meeting edges, a vertical rotary shaft mounted in bearings which are fixed on one of the doors near their meeting line whereby the shaft is held from lateral movement relative to the door on which it is mounted, toothed gears fixed on the shaft 80 near its ends and arranged beyond the top and bottom edges of the door, corresponding toothed racks fixed on the car body and engageable by said gears, the solid and un-toothed parts of said racks being arranged 85 out of the paths of the solid parts of the gears so that the gears may pass the racks as the doors move to closed position, and means for turning said shaft.

2. In a refrigerator car having a door 90 opening and a door pivoted to swing at one edge about a fixed vertical axis, the combination with upper and lower keepers secured to the outer face of the car wall above and below the door opening, each of said keepers 100 having a short rack extending outwardly from the car wall in a plane perpendicular thereto, of a door-operating shaft provided at its upper and lower ends with gears disposed above and below the upper and lower 105 edges, respectively, of said door and in co-operative alinement with said keeper racks, and bearings on said door near its free edge in which said shaft is mounted, said bearings 110 confining said shaft to a rotatable movement only on said door, rotation and translation of the shaft gears inward and outward past the keeper racks completely effecting the final closing and initial opening movements of the door.

3. In a refrigerator car having a door 115 opening and a door pivoted to swing at one edge about a fixed vertical axis, the combination with upper and lower keepers secured to the outer face of the car wall above and below the door opening, each of said keepers having a short rack extending outwardly from the car wall in a plane perpendicular thereto, of a door-operating shaft provided at its upper and lower ends with gears 120 disposed above and below the upper and lower edges, respectively, of said door and in co-operative alinement with said keeper racks, bearings on said door near its free edge in which said shaft is mounted, said 125 130

bearings confining said shaft to a rotative movement only on said door, rotation and translation of the shaft gears inward and outward past the keeper racks completely 5 effecting the final closing and initial opening movements of the door, each of said shaft gears having an elongated tooth adapted to initially engage the outer end of

the corresponding keeper rack to facilitate proper registration of the gears and racks 10 during final closing movements.

In witness that I claim the foregoing I have hereunto subscribed my name this 25th day of Oct., 1917.

SVEN J. STRID.
